UNITED STATES PATENT OFFICE.

WILLIAM HENRY WAKFER, OF NORWOOD, ENGLAND.

COCK OR VALVE.

No. 913,861.

Specification of Letters Patent. Patented March 2, 1909.

Application filed November 2, 1906. Serial No. 341,748.

To all whom it may concern:

Be it known that I, WILLIAM HENRY WAKFER, a subject of the King of Great Britain, residing at No. 67 Whitworth road, 5 Norwood, in the county of Surrey, England, have invented an Improved Cock or Valve, of which the following is a specification.

This invention relates to an improved cock or valve of the type consisting of a casing having a taper bore or seating within which bore is mounted a taper plug not quite reaching to the bottom of the casing.

In order to enable the invention to be readily understood reference is made to the 15 accompanying drawings in which:

Figure 1 is a side elevation of a cock made according to this invention. Fig. 2 is an end elevation and Fig. 3 is a longitudinal section thereof. Fig. 4 is a plan view showing 20 gripping faces on the casing. Fig. 5 is a section of a fragment of the casing showing a gripping face in the seating. Fig. 6 is a similar view of a hot water tap or cock also constructed according to this invention. 25 Fig. 7 is a transverse section of a modification. Fig. 8 is a section of a two way cock the section being taken on a plane at right angles to the axis of the taper plug. Fig. 9 is a plan section of another two way cock 30 which is particularly suitable for baths to be supplied with hot and cold water. Fig. 10 is a sectional view on the line 8-8. Fig. 7 and Figs. 11, 12 and 13 are similar views of other modifications and Fig. 14 is an inverted plan view of a cap formed with a gripping face.

Referring to Figs. 1, 2 and 3 the lower end of the plug *a*, best seen in Fig. 3, is made with a shallow cylindrical recess *b* and provided with a coiled spring *c* which constantly tends to raise the plug *a* vertically and out of contact with the inner sides of the casing *d*. The casing *d* is provided with a screwed cap *e*, having a hole in the middle 45 through which the valve stem *f* passes, the upper end of said stem being made square or otherwise fashioned for receiving a key or handle *g* by which the valve is turned to the open and closed positions. The upper 50 end of the valve casing is suitably provided with an external screw thread adapted to receive the screw cap *e* which is provided with a corresponding internal thread, and in order to make a tight joint between the screwed

cap and the casing *d* a washer *h* of india rubber is provided of such an internal diameter as to more or less fit the stem *f* of the plug and of such an external diameter as to rest on the top or barrel of the casing. In order to prevent the screwed cap from coming 55 unscrewed by any shock or concussion or from being screwed up too tightly or unscrewed by reason for instance of any friction which may exist between the stem of the plug and the hole in the screwed cap 60 through which the stem of the plug passes, the upper edge or face *i* of the top or barrel of the casing is milled or provided with small projections or with serrations or recesses as shown in Fig. 4 which bite into the india 65 rubber washer and are thus adapted to lock the screwed cap so as to prevent it from being turned unintentionally or the serrations or gripping face may be formed on the cap as seen in Fig. 14, and the adjoining surface 70 at *k* inside the barrel may also be milled or similarly fashioned if desired as shown in Fig. 5. The upper end or flat surface of the plug is provided with a packing *l* of asbestos or other suitable material so as to make a 75 tight joint between the outer circumference of the plug *a* and the stem of the plug *f*, and there is preferably another washer *m* of india rubber surrounding the stem and of a 80 diameter equal to the internal diameter of 85 the casing; or the washer *h* may be molded so as to be smaller in diameter below so as to partly rest on the upper edge of the casing and to partly fill the casing, the single 90 washer then being as shown in Fig. 6 and marked *o* of a section corresponding to the combined sections of the washers *h* and *m*. This washer *o* or these washers *h* and *m* (see Fig. 3) may be made of ordinary rubber or partly of india rubber and partly of fabric. 95 The said washer or washers or their equivalent or equivalents is or are intended to fulfill a double purpose, namely to provide packing material and a yielding resistance or spring to the upward movement of the plug 100 as aforesaid.

The screw cap *e* is suitably made with external means such as milled edges (two such milled edges being shown in the constructions illustrated by Figs. 3 and 4) so as to permit 105 of its being screwed down and adjusted by hand. If desired and in cases where cocks are exposed to violent usage, the casing is

suitably strengthened on each side as aforesaid by ribbing *n* (Figs. 1 and 2) whereby equal strength as compared with a thicker casing, generally is obtained, while effecting 5 a saving in the amount of metal used.

According to a modification and as shown in Fig. 7 the base or larger diameter of the plug *p* may be at the bottom and that end of the barrel or casing *q* is then provided with 10 the screwed cap *r* or the like, and the space between the interior surface of the cap and the base of the plug is occupied by the packing *s* and india rubber disks *t* and *u* or the like. The upper part of the plug is reduced 15 in diameter to form a stem *v* and is surrounded by a spring *w* or by a packing and a spring and that part of the stem which passes through the casing is provided with a square or the like for the key or handle as is usual. 20 Cocks of this kind may be provided with three inlets or branches and a particular application of such a construction is shown in Fig. 8 in which case one branch marked *x* may be used for lubricating when the plug 25 shuts off the inlet *y* for the steam or other motive fluid for example or both the steam inlet *y* and the steam outlet *z*. In that case the oil is poured into the branch and fills the hollow plug more or less as required. Then 30 a partial turn of the plug to the left, closes the inlet *x*, opens the passage for the steam from *y* by way of *z* to the motor and the oil is passed in with the steam to lubricate the piston and valve or valves. In connection 35 with rock drills which have to stand a large amount of rough usage the branches *x*, *y* and *z* may all be screwed, so that if the thread of one branch or the branch itself is damaged that one may be used for lubrication purposes and the other two for the inlet and 40 outlet of the motive fluid.

A cock of this description is also applicable to baths for hot and cold water but preferably a hot and cold water cock for baths is 45 made as shown in Figs. 9 and 10 in which there are two inlets 1 and 2 at the side and one outlet 3, say at the bottom of the plug. The ports 4 and 5 in the plug are so arranged that the plug may shut off the supply from 50 either inlet entirely, or only one inlet may be open, while the other is shut or both may be fully open as shown or they may be more or less open. The said ports 4 and 5 are of different sizes so that either the total area of 55 the inlets 1 and 2 may be open as is the case in Fig. 9 or the plug may be given a half turn till the port 5 registers with inlets 1 and 2 in which case only half the amount of hot and cold water will pass. In the present case 60 the outlet is formed in one with a screwed cap 6 which screws on the casing 7 and makes a tight joint by means of a washer 9. Further the outlet 3 is grooved externally so that a flexible tube with a rose or spray may

be put on same, for giving a shower bath, 65 douche or the like.

According to another modification as shown in Fig. 11 the plug 10 is made hollow and the inlet is at the bottom while the outlet port is at the side and in this case, where 70 the pressure of the liquid always tends to raise the plug the packing and the resilient washer or washers may be at the top of the plug as firstly described. Or as shown in Fig. 12 the inlet may be at the side and the 75 outlet at the bottom of the hollow plug 11. Or as shown in Fig. 13 the plug 12 may be closed at the bottom and the port may be right through the plug.

Cocks constructed according to this invention are equally applicable to high and low pressure or to high and low temperature liquids or fluids, they are designed to prevent the binding or grinding of the plugs under 80 all circumstances and to avoid the deterioration 85 and waste as well as loss of power through leakage. Besides these advantages the effect of the india rubber disk or washer exerting a pressure on the plug prevents the latter from turning by vibration or concussion, which in the case of rock drills and other machinery often occurs if ordinary 90 plug taps or valves are employed.

The invention is not limited to the constructions shown but embraces equivalents 95 thereof the scope being clearly defined by the claims.

What I claim as my invention, and desire to secure by Letters Patent is:—

1. In a plug cock, the combination with a 100 tapering casing open at the wider end and formed with shallow milling serrations and threaded externally at said end, an internally threaded cap adapted to screw on to said end, a tapering plug having a stem at one end 105 forming an annular shoulder, a packing composed chiefly of rubber having an inner portion occupying the space within the casing and between the plug and the screw cap and an outer portion of a diameter approximating the internal diameter of the screw cap, asbestos packing between said elastic packing and the plug and means for pressing said cap upon the casing whereby the outer portion of the elastic packing is nipped between 110 the cap and the wider end surface of the casing effecting a tight joint between these parts and the remainder of the packing is forced into the casing against one end of the plug so as to make a tight resilient joint between the 115 plug and the casing and whereby said elastic packing is prevented from rotating with the plug.

2. In a plug cock, the combination with a 120 tapering casing open at the wider end and formed with shallow milling serrations and threaded externally at said end, an internally 125 threaded cap adapted to screw onto said end,

a tapering plug having a stem at one end forming an annular shoulder, a packing composed chiefly of rubber having an inner portion occupying the space between the stem of the plug and the casing and an outer portion of a diameter approximating the internal diameter of the screw cap, asbestos packing between said elastic packing and the plug, and means for pressing said cap upon the casing whereby the outer portion of the elastic packing is nipped between the cap and the wider end surface of the casing effecting a tight joint between these parts and the remainder of the packing is forced into the casing against the shoulder and spindle of the plug so as to make a tight resilient joint between the plug and the casing whereby said elastic packing is prevented from rotating with the plug.

20 3. In a plug cock, the combination with a tapering casing open at the wider end and formed with shallow milling serrations and threaded externally at said end, an internally threaded cap adapted to screw onto said end, 25 a tapering plug having a stem at one end forming an annular shoulder, a packing com-

posed chiefly of rubber having an inner portion occupying the space between the stem of the plug and the casing and an outer portion of a diameter approximating the internal 30 diameter of the screw cap, asbestos packing between said elastic packing and the plug, means for pressing said cap upon the casing whereby the outer portion of the elastic packing is nipped between the cap and the wider 35 end surface of the casing effecting a tight joint between these parts and the remainder of the packing is forced into the casing against the shoulder and spindle of the plug so as to make a tight resilient joint between the plug 40 and the casing and whereby said elastic packing is prevented from rotating with the plug, and a spring adapted to force the plug against the packing.

In testimony whereof I have signed my 45 name to this specification in the presence of two subscribing witnesses.

WILLIAM HENRY WAKFER.
